UNITED STATES PATENT OFFICE.

ROBERT L. LINDSTROM, OF TUSTIN, MICHIGAN.

SCREEN ATTACHMENT.

1,162,625.

Specification of Letters Patent. Patented Nov. 30, 1915.

Application filed February 28, 1914. Serial No. 821,754.

To all whom it may concern:

Be it known that I, ROBERT L. LINDSTROM, a citizen of the United States, residing at Tustin, in the county of Osceola and State 5 of Michigan, have invented new and useful Improvements in Screen Attachments, of which the following is a specification.

This invention relates to screen attachments, and particularly to attachments for 10 window screens, door screens or the like; and it has for its object the provision of a device of this character which will prevent insects, such as flies that customarily accumulate on one side of the screen and on the 15 inside of the room to approach a portion of the screen where they will be compelled to pass to the outside.

With the above and other objects in view, the invention consists of certain novel features of construction, combination and arrangement of parts, as will be hereinafter described and claimed.

In the accompanying drawings:—Figure 1 is a perspective view of one side of the 25 screen; Fig. 2 is a perspective view of the opposite side thereof; and Fig. 3 is a vertical section through the screen.

The screen as herein contemplated may be used upon windows, doors or the like, and 30 it is especially designed for the purpose of minimizing the possibility of flies or the like entering the room from the outside and also causing such insects as may accumulate on the inner surface of the screen to 35 travel to a point where they will be compelled naturally to escape to the outside. In view thereof use is made of a frame 1 consisting of the usual side bars 2, 2, a top bar 3 and a bottom bar 4. To one side of the 40 frame is arranged a sheet of foraminated material 4' such as the usual wire, and as shown this material is secured along its side edges, as at 5, to the side bars 2, 2, while at the lower edge the material is secured as 45 at 6 to the bar 4. The upper edge of the material is embraced by a metallic deflector 7 which is located below the door 3 for a slight distance and arranged with relation thereto so as to define therewith an intervening exit passage approximately throughout the width of the frame. The said member 50 7 is disposed at an angle to the plane of the main body portion of the material and in view thereof it is evident that insects after escaping on the body of the screen to 55 a point beneath the member 7 will on their

final effort to ascend contact with the part 7 and thereby be deflected away from the opening between the part or member 7 and the mentioned adjacent edge of the bar 3. 60

At the back of the screen is an attachment 65 consisting of a strip of material 8 secured at its sides to the side bars 2 of the frame and secured along its upper edge to the back of the bar 3. In this manner the material 8 is spaced from the foraminated material at the front of the screen. It will thus be seen that the flies or other insects that travel in an upward direction on the rear surface of the material 4' will finally pass 70 into the space 9 between the materials 4' and 8.

Secured to the lower edge of the material 8 is a guard 10, which is preferably formed of sheet metal, the lower edge of which is 75 rolled over the lower edge of the material 8 and as shown said guard is provided with an angular portion 11 located in a plane below but substantially parallel with the plane of the deflected portion 7, which extends in the direction of the opening between the bar 3 and the member 7. The portion 11 of the guard is provided with end flanges which bear against the inner surfaces of the bars 2, 2 and between its ends the said portion 80 11 is provided with integral spacing extensions which extend over against the material 4'. These extensions are provided with integral spurs 12 that are adapted to be extended between the material 4' and 85 90 adapted to be upset thereagainst. The portion 10 of the guard 11 thus serves to restrict the size of the passage 9 in an upward direction and to minimize the possibility of the flies from passing in a downward direction 95 through the space between the material 4' and the portion 11 of the guard 10.

I claim:—

In a screen attachment comprising a frame with a sheet of foraminous material secured 100 on one side thereof, an outturned deflecting portion formed on said sheet at an angle to said frame and disposed to form a horizontal passage between the upper edge of said frame and the deflecting edge of said portion, a foraminous sheet on the opposite side of said frame extending below the top thereof with an inturned end extending nearly to the opposite foraminous sheet to form a passage therebetween said end being 105 110 inclined in a plane below but substantially parallel with the plane of inclination of the

said deflecting portion, supporting members in spaced relation on said inclined end, adapted to extend through the adjacent foraminous sheet and fasten on the opposite 5 side thereof slightly below the said out-turned deflecting portion thereon, substantially as described.

In testimony whereof I affix my signature in presence of two witnesses.

ROBERT L. LINDSTROM.
